Inventor
David Stuart.

Geo. P. Himmel, Attorney

UNITED STATES PATENT OFFICE.

DAVID STUART, OF BERLIN, NEW HAMPSHIRE.

BEDPLATE FOR BEATER ENGINES.

Application filed August 4, 1921. Serial No. 489,782.

To all whom it may concern:

Be it known that I, DAVID STUART, a subject of the King of England, residing at Berlin, in the county of Coos and State of New Hampshire, have invented certain new and useful Improvements in Bedplates for Beater Engines, of which the following is a specification.

This invention appertains to certain improvements in stock beaters or beating engines, and more particularly to a novel form of bed plate construction adapted for cooperation with the beating roll or rolls of such beaters or engines.

The principal object of the invention is to provide for a bed plate construction of the class mentioned, and one of the nature to facilitate the feeding or drawing of paper pulp or stock through the beating roll or rolls at a faster rate than now obtains in the operation of such devices.

Another object of the invention is to provide for a bed plate as characterized, and one wherein the increased feeding or drawing of the paper pulp or stock through the beating roll or rolls is successfully accomplished in a manner to prevent the usual tearing or breaking up of the length of the fibre in the pulp or stock, such as otherwise seriously diminishes the strength of the latter, and, as a consequence thereof, causes the product of the pulp to be inferior in quality.

A further object of the invention is to provide for a bed plate of the character mentioned, and one of a peculiar nature and constructions, whereby to create a suction between the same and the beating roll or rolls in a manner to affect the faster feeding or drawing of the pulp or stock through the engine than that now obtains in all constructions of such engines.

Another object of the invention is to provide a bed plate of the type as hereinbefore mentioned, and one embodying a novel construction and arrangement of parts thereof, whereby to discharge currents of air at points between the opposed surfaces of the bed plate and the beating roll or rolls for freeing the pulp which might otherwise tend

to clog or obstruct the passage way or ways thereof.

With the foregoing and other objects in view, the invention resides in a certain novel and useful construction and arrangement of parts as will be hereinafter more fully described, set forth in the appending claims, and illustrated in the accompanying drawings, in which:

Figure 1 is the top plan view of the preferred embodiment of the bed plate;

Fig. 2 is a side elevation thereof, partly in section;

Fig. 3 is a vertical transverse section taken on the line 3—3 of Fig. 1;

Fig. 4 is a fragmentary side elevation of a beater roll showing the association of the improved bed plate therewith, the latter being in end elevation, and,

Fig. 5 is a fragmentary front elevation of the roll as in Fig. 4 with the bed plate in side elevation.

Referring to the drawing, wherein similar characters of reference designate corresponding parts in the several views thereof, the preferred embodiment of the invention as shown therein comprises three elongated hollow casings 10, 11, and 12, substantially rectangular in cross section, and spaced in parallel relation one with respect with the other, and in a manner to provide a space of a greater width between the castings 10 and 11 than the space between the castings 11 and 12. The castings 10, 11 and 12 are set up in the positions as stated, so as to rest upon one of their narrow faces, and have their upper narrow faces perforated throughout their length with a series of staggered openings 13 in communication with the hollow interiors thereof.

Arranged in the spaces between the several castings 10, 11 and 12, are a series of alternately arranged filler plates 14, and division plates 15, the plates 14 being of a greater thickness than the plates 15, and are clamped into position by means of transversely extending bolts 16, which are threaded on their oppositely projecting ends to receive the washers 17 and the securing nuts 18 thereof. Interposed between the outer

of the plates 15 and the castings 10, and 12, are end plates 19 and 20 of equal or a greater thickness than the said plates 14, whereby to assure of all of the several plates 14 and 15 being clamped tightly together in uniform contacting relation one with respect to the other. The several plates 14, 15, 19 and 20 are of a greater width or height than the castings 10, 11 and 12, which are of an equal height one relatively to the other, and the portions of the several plates above the castings are suitably fastened together by a series of transversely extending bolts 21, clamping the same between the nuts 22 threaded onto the oppositely projecting ends of the same. The faces of the two sections of the bed plate, as formed by the upper edges of the several plates 14, 15, 19, and 20, are inwardly curved in the transverse direction on a line approximating the arc of a circle throughout the length thereof, whereby to conform to the curvature of a beater roll *a* with which the bed plate is to be associated. The several plates 15 are of a slightly greater height than the several plates 14, whereby to provide a series of longitudinally extending grooves or channels 23 arranged in two sets, one spaced to either side of the central casting 11, the top edges 25 of both sets of filler plates 14 and the plates 15 being correspondingly inclined outwardly in opposite directions from the transverse center of the base plate, so that the grooves or channels 23 are of equal depth throughout their respective lengths. As shown in Figure 1, however, the opposite end portions of the bed plates, to either side of the transverse center thereof, are preferably disposed in angular relation, one with respect 30 to the other, which arrangement acts to maintain a more even distribution of the pulp over the surface of the bed plate than would otherwise be the case.

In the use of a bed plate constructed and arranged in accordance with the invention, the same is to be positioned beneath a beater roll *a* substantially as is shown in Fig. 4, and, as the power is supplied to the roller shaft *b*, pulp will be fed to the roll 45 and the bed plate correspondingly with the rotation of the former. The pulp is directed inwardly of the transverse center of the bed plate, as shown by the arrows *c* in Fig. 1. By reason of the angular formation of the opposite portions of the bed plate, and of the oppositely disposed sets of grooves or channels 23, the pulp will be spread uniformly over the entire surface of the bed plate. During the rotation of the roll *a*, a suction will be created between the opposed surfaces of the same and the bed 50 plate, and in several grooves thereof, whereby the flow of pulp through the machine is greatly facilitated or accelerated, as compared to the rate of flow obtaining in the

usual and known constructions of beater engines. At desired intervals, or when otherwise necessary, compressed air is admitted to the castings 10, 11, and 12 through the piped inlets 10', 11', and 12' complementary thereto, and will discharge upwardly of the openings 13, and act to prevent the clogging of the grooves or channels 23 of the bed plate with the pulp, and to otherwise clear the same and keep them free for the creation of the suction, as aforesaid. 70

It is well understood that, while a preferred embodiment of the bed plate has been described and illustrated herein in specific terms and details of construction and arrangement, various changes in and modifications of the same may be resorted to without departing from the spirit of the invention, or the scope of the claims appended hereto. 80

Having thus fully described the invention, what is claimed, is:—

1. A bed plate for beating engine rolls having a grooved surface cooperative with the adjacent periphery of a beating roll, whereby a suction is created therebetween for facilitating the feed of the pulp stock through the engine, grooves in said bed plate extending longitudinally thereof and at right angles to the direction of flow of the pulp across the same and inclining outwardly and downwardly from the transverse center of the bed plate, whereby to effect an even distribution of the pulp in its flow between the roll and said bed plate, and means for discharging compressed air to said bed plate and between the opposed surfaces thereof and said beating roll. 95

2. A bed plate for beating engine rolls having a grooved surface cooperative with the adjacent periphery of a beating roll, whereby a suction is created therebetween for facilitating the feed of the pulp stock through the engine, said bed plate having its opposite end portions angularly disposed to either side of the transverse center thereof, and means for discharging compressed air to said bed plate and between the opposed surfaces thereof and said beating roll. 105

3. A bed plate for beating engine rolls formed to provide spaced grooved sections, hollow castings disposed between and to either side of said sections, and means for supplying compressed air to the interiors of said casting, said castings, each having a plurality of outlet openings for discharging the compressed air upwardly of and between the bed plate and beating roll for preventing the clogging up of the grooves thereof. 110

4. A bed plate for beating engine rolls formed to provide spaced sections, each of said sections being made up of alternately arranged division plates and fillers to pro- 115 120 125 130

vide longitudinally extending grooves in the upper faces thereof, hollow castings disposed between and to either side of said sections, and means for supplying compressed air to the interiors of said castings, said castings each having a plurality of outlet openings for discharging the compressed

air upwardly of and between the bed plate and beating roll for preventing the clogging up of the grooves thereof. 10

In testimony whereof I affix my signature hereto.

DAVID STUART.
